UNITED STATES PATENT OFFICE.

OLA F. HESLAR, OF MARION, INDIANA, ASSIGNOR TO INDIANA MANUFACTURING & ELECTRIC CO., OF MARION, INDIANA, A CORPORATION OF INDIANA.

VERNIER RHEOSTAT.

Application filed October 30, 1922, Serial No. 597,846. Renewed February 17, 1926.

This invention relates to a vernier rheostat, particularly adapted for use in connection with a radio receiving set.

Heretofore the resistance units or rheostats have been so constructed that there is an appreciable difference in resistance between succeeding coils of the resistance wire, whereby said resistance could not be uniformly and variably controlled. It has usually been necessary, therefore, in constructing a vernier rheostat to provide a second auxiliary adjustment for enabling such difference in resistance to be compensated.

The main feature of this invention is to construct a rheostat of a simple and compact arrangement for eliminating the necessity of providing an auxiliary resistance control to make it a vernier rheostat. This is accomplished by providing a resistance coil with a sliding contact member so arranged as to be engageable with any point thereon. The length of the resistance winding may be ever so slightly varied by the slight variation of the point of contact thereon so as to enable a fine adjustment of the resistance without the use of an intermediate auxiliary control. Such a resistance unit as is contained in this type of rheostat is uniformly variable throughout and thereby permits a fine variation of resistance without necessitating compensation for the difference in resistance of the usual coils or loops.

In connection with a radio receiving circuit, this rheostat allows an absolute control over the flow of electrons in a vacuum tube which does not necessitate a change in wave length or frequency which is necessary to compensate for the resistance between the coils or loops of the usual type of rheostat. In tuning a receiving instrument for the reception of certain wave lengths, such fine adjustment may be had by means of this type of rheostat as to completely control the flow of electrons so as to eliminate the necessity of adjustment by varying the condenser, vario-coupler or variometer, and also with a single adjustment rather than the double adjustment necessary in such a construction as is embodied in a vernier filament controlled rheostat. This permits of better results in the receiving circuit, inasmuch as the variable condenser, variometer or vario-coupler may be concentrated on adjustment to the wave length, instead of being ad-

justed to compensate for variations of resistance in the rheostat.

The full nature of the invention will be understood from the accompanying drawings and the following description and claims.

In the drawings, Fig. 1 is a plan view of the rheostat mounted upon an instrument board shown in cross section, with the sliding contact finger moved to non-resistance position. Fig. 2 is the same as Fig. 1 showing the contact finger moved to full resistance position. Fig. 3 is a rear elevation of the rheostat. Fig. 4 is a central horizontal section therethrough.

In the drawings there is shown an instrument board 10 which is usually set in a vertical position. Extending through a suitable opening in said board, there is a shaft 11 having an adjusting knob 12 secured on the outer end thereof by means of the screw 13, said knob carrying the usual dial 14. Secured to the inner wall of the board 10, there is a supporting disk 15 formed of any suitable insulating material, such as hard rubber or fiber.

Mounted on the inner end of the shaft 11 and keyed thereto, there is a rotating drum 16 adapted to be rotated by the shaft 11 upon the turning of the knob 12. The metal contact disk 17 is embedded in the drum 16 which is also made of an insulating material, such as hard rubber or fiber, and is secured on the outer face thereof by the pins 18. The end of the shaft 11 is insulated from the plate 17 by the washer 19 which is also made of suitable insulating material. The periphery of the drum 16 is provided with spiral grooves or screw threads in which there is wound a resistance wire 20, said wire being wound about the periphery of said drum in the grooves formed by said screw threads. The drum being made of insulating material, and the windings or loops of the resistance wire being separated by the screw threads, each loop will be insulated from the other. One end of the wire 20 is secured in position by the pin 21 having a head 22, and the other end of said wire is adapted to extend radially into said drum through a suitable opening bored therein to the plate 17 where it extends to a hole drilled therein and is soldered in position. For further securing the last mentioned end

of the wire in place, it is wedged in the radial hole of the drum by the pin 23 having a head 24.

Rigidly mounted upon the supporting disk 15, there are brackets 25 and 26, said brackets being insulated from each other by said disk. Mounted on the bracket 25, there is a contact arm 27 secured in position by the bolt and nuts 128 which comprises one of the terminals to which a lead wire is secured. The free end of the contact arm 27 is bifurcated, as shown in Fig. 3, so that it yieldingly engages the contact plate 17 through which it is always in electrical contact with the outer end of the resistance wire 20. Pivotaly mounted on the bracket 26, there is a movable contact arm 28 having an inwardly extending pointed finger 29. The arm 28 is in the form of a plate spring which tapers to the point 29 which is constantly in engagement with the resistance wire 20 under spring tension. Said arm 28 is pivotally mounted at its base upon the bracket 26 by the bolt and nuts 30 which form the other terminal in the circuit.

In operation, upon connecting the rheostat in the circuit, the terminals 128 and 30 are secured to the lead wires, whereby the current will pass through the terminal 128, contact arm 27 and plate 17 to the inner end of the resistance wire 20. It will then pass through the wire 20 about the periphery of the drum to the point of engagement therewith by the finger 29, through the movable contact arm 28, the terminal 30 and the lead wire attached thereto. It will be obvious that the resistance of the rheostat will depend upon the length of that portion of the resistance wire through which it passes. Such resistance may be varied by turning the knob 12 which will rotate the drum 16. Such rotation of the drum with respect to the movable arm 28 which is pivotally mounted to the stationary part of the rheostat will cause the engaging finger 29 thereof to be guided in the thread-like peripheral grooves of said drum in constant contact with the resistance wire. This movement will cause the finger 29 to move back and forth across the surface of the drum from the position shown in Fig. 1 to that shown in Fig. 2. When the finger reaches either end of the wire, it will be stopped by its engagement with the heads 22 and 24 of the pins 21 and 23. This contact with said heads limits the rotary movement of the drum and the lateral movement of the arm, so that it cannot move out of the

grooves and lose contact with the resistance wire.

For further illustration of the invention, the drum may contain about two feet of resistance wire wound about the periphery thereof, said wire having resistance of substantially $2\frac{1}{2}$ ohms per foot. This would give a maximum resistance when the finger is at the point shown in Fig. 2 of substantially $5\frac{1}{2}$ ohms, which is a sufficient maximum resistance for ordinary purposes.

From the foregoing it will be apparent that a very fine adjustment of resistance may be obtained and no compensation will be necessary, such as is required where the movable contact jumps from loop to loop or coil to coil.

The invention claimed is:

1. A rheostat adapted to be mounted on a stationary panel, comprising a rotatable drum having spiral grooves formed about the periphery thereof, means for rotating said drum, a resistance wire wound in said grooves, an annular contact ring mounted on one side of said drum and connected with one end of said resistance wire, a brush adapted to contact with said ring, and a pivotally-mounted finger having its free end extending over the periphery of said drum in contact with said resistance wire and adapted to make sliding contact therewith, whereby the rotation of said drum will cause the spiral grooves thereon to move said finger about its pivotal mounting so as to vary the position of contact thereof with said wire.

2. A rheostat adapted to be mounted on a stationary panel, comprising a rotatable drum having spiral grooves formed about the periphery thereof, means for rotating said drum, a resistance wire wound in said grooves, an annular contact ring mounted on one side of said drum and connected with one end of said resistance wire, a brush adapted to contact with said ring, a binding post connected with said brush, a second binding post mounted on said panel, and a resilient contact finger pivotally mounted on said second binding post and extending over the periphery of said drum having its free end extending into said spiral groove in engagement with said wire, whereby the rotation of said drum will cause the spiral grooves thereon to move said finger about its pivotal mounting so as to vary the position of contact thereof with said wire.

In witness whereof, I have hereunto affixed my signature.

OLA F. HESLAR.
